W. C. BROWN.

VALVE GRINDER.

APPLICATION FILED OCT. 20, 1917.

1,314,851.

Patented Sept. 2, 1919.

UNITED STATES PATENT OFFICE.

WILLIAM C. BROWN, OF NILES, OHIO.

VALVE-GRINDER.

1,314,851.

Specification of Letters Patent. Patented Sept. 2, 1919.

Application filed October 20, 1917. Serial No. 197,790.

To all whom it may concern:

Be it known that I, WILLIAM C. BROWN, a citizen of the United States of America, residing at Niles, in the county of Trumbull and State of Ohio, have invented certain new and useful Improvements in Valve-Grinders, of which the following is a specification.

My present invention relates to improvements in valve-grinders for use on internal combustion engines and motors in general; and specific reference is hereby made to Letters Patent No. 1,150,874, of Aug. 24, 1915, issued to Morris, *et al.*, of which I am 15 the sole licensee (of record), and I herein claim nothing protected by said patent.

My improvement consists of elements to be easily assembled and, temporarily, operatively located in position to grind the 20 valves of such engines when built with either removable caps or heads; and the objects of my invention are, first, so to do; second to greatly reduce the number of working parts and the cost thereof; third to shorten the 25 time required to grind the valves; and, fourth, to enable the operator to grind one or a plurality at a single operation, as required.

I accomplish those objects by the mechanism described in the following specification, clearly expressed in the claims, and illustrated in the drawings, in which—

Figure 1 shows in elevation a portion of the housing of an explosive engine, in part 35 broken away, with a cylinder and a valve and one form of my invention attached.

Fig. 2 is a top plan view of the engine with head H removed.

Fig. 3 is a plan of a bar and an elevation 40 of a rivet, as used in my invention, and Fig. 4 shows an element described.

Fig. 5 illustrates a modification, and Fig. 6 shows my invention as used in series.

Like characters refer to similar parts 45 throughout the several views.

Most explosive or combustion engines have a head H, within which are located cylinders C, with piston heads and piston rods operatively connected with a crank 50 shaft by pitmen; and in Fig. 1 I have shown one which has a cover or top, T, also shown in Fig. 2; and to which top is bolted a removable head, H, which covers the gas chamber G, the cylinders and certain other 55 of the working elements and wirings, and into which are screwed the spark plugs 1, 1.

In the top T are formed valve seats 2, 2', etc., and a plurality of regularly spaced bolt holes 13, 13, etc.

The head H is provided with corresponding screw holes 3', 3'', so that by the removal of the screws 4 the head H can be lifted off to grind the valves which consist of the valve seats 2 and the valve heads 5.

In order to grind one valve, as 2, 5, I 65 provide a support 6, consisting of a vertical bar 6', with a horizontal arm 6'', having a hole 7, through it (Fig. 4); and a horizontal base 8 having a slot 9.

The head H having been removed the support 6 is fastened to the top, T, by a screw 4 through the slot 9 and hole 3' after the stem 10 (Fig. 1) has been passed through hole 7 of the arm 6''.

Thereupon the screw driver edge 11 at 75 the base of the stem 10 fits into a kerf 12, in the valve head 5.

A handle 14 having a square hole 15, is then placed on the end of the stem 10 and by means of it the operator can oscillate 80 the valve head 5 in the valve seat 2, with or without rouge or the like, until that valve is true.

In order to save the operator from the necessity of manually retaining the grinding parts in contiguous relation, I introduce 85 a spiral spring, S, coiled about the stem 10, and below an annular enlargement 16 thereon, which threads into the hole 7 (Figs. 1 and 4), which spring serves to press 90 the grinding parts together evenly.

To grind the valve 2 the support 6 may be located and held by the screw 4 through the hole 13; and then turned to grind the next valve, comprising seat 2 and a corresponding valve head 5', valves 2'' and 2'', etc.

When it is desired to be grinding more than one valve at a time I provide a bar 17 Figs. 3 and 6 with a plurality of holes, 100 18, 18, and loose rivets 20. A series of supports 6, 6, etc., having been located with a series of edges 11, 11, fitting into kerfs 12, 12, of several valves, each support being equipped with its handle 14, 14, etc., the bar 105 17 is laid on top of them all and rivets 20, 20, dropped through the holes 18, 18 which correspond to the several holes 19, 19 of the handles; whereupon a forward and backward movement given to the bar 17, 110 oscillates all of the grinding valve heads in their respective valve seats.

On engines which do not have tops T, the valve heads are exposed and covered by a removable threaded cap similar to the plug 21 shown in Fig. 5, but usually slightly larger in diameter than the threaded holes 7 in the arm 6.

To grind those I provide a special plug 21 of the right size and thread, as shown equipped with stem 10', thread 16', a spring 10 S' and an edge 11', which temporarily replaces the plug that comes with the engine, and is reciprocated or oscillated by the handle 14'.

On this modification a plurality of plugs (21) are used and their respective handles 14' are operated conjointly and simultaneously by a bar (as above), when it is desired to grind more than a single valve at a time.

I claim:—

1. The combination of a plurality of valve grinders of the kind described, hav-

ing individual oscillatory handles with supplemental holes therethrough; with an operating bar having a corresponding plurality of holes and a plurality of removable locking elements fitting said holes, for the purpose set forth.

2. In a device of the kind described for grinding valves of combustion engines and having operating handles with holes therethrough; a removable element consisting of a bar with a plurality of properly spaced holes therethrough and removable rivets fitting said holes in said element and handles, as shown and described and for the purpose set forth.

In testimony whereof I affix my signature in the presence of two witnesses.

WILLIAM C. BROWN.
